UNITED STATES PATENT OFFICE.

CHARLES ROHLFS, OF BUFFALO, NEW YORK.

DESIGN FOR A STAND FOR CHAFING-DISHES OR CASSEROLES.

SPECIFICATION forming part of Design No. 36,972, dated June 14, 1904.

Application filed May 20, 1904. Serial No. 208,964. Term of patent 7 years.

To all whom it may concern:

Be it known that I, CHARLES ROHLFS, a citizen of the United States, residing at Buffalo, in the county of Erie and State of New York, 5 have invented a new, original, and ornamental Design for a Stand for a Chafing-Dish or Casserole, of which the following is a specification, reference being had to the accompanying drawing, forming a part thereof.

o The drawing is a perspective view of a stand for a chafing-dish or casserole disclosing the design.

What I claim as new, and desire to secure by Letters Patent, is—

The ornamental design for a stand for a 15 chafing-dish or casserole as herein shown.

CHARLES ROHLFS.
